UNITED STATES PATENT OFFICE.

THOMAS ALFRED HEARSON, OF 5 WESTCOMBE PARK ROAD, BLACKHEATH,
COUNTY OF KENT, ENGLAND.

ROTARY ENGINE.

SPECIFICATION forming part of Letters Patent No. 301,235, dated July 1, 1884.

Application filed October 8, 1883. (No model.) Patented in England March 1, 1883, No. 1,118; in France August 28, 1883, No. 157,267; in Belgium August 30, 1883, No. 62,456, and in Germany September 2, 1883.

To all whom it may concern:

Be it known that I, THOMAS ALFRED HEARSON, a subject of the Queen of Great Britain, residing at 5 Westcombe Park Road, Blackheath, in the county of Kent, England, have invented certain new and useful Improvements in Rotary Engines and Governors and Apparatus Connected Therewith, (for which I have received Letters Patent in Great Britain, No. 1,118, dated March 1, 1883; in France, No. 157,267, dated August 28, 1883; in Belgium, No. 62,456, dated August 30, 1883, and in Germany, dated September 2, 1883,) of which the following is a specification.

The chief object of this invention is to provide an engine in which the moving parts shall not be subjected to the great rate of change of velocity which occurs on the reversal of the stroke of the ordinary reciprocating engine, so that, a very great reduction in the magnitude of the forces due to change of momentum being made, a very high speed of revolution may be easily obtained. The process of the ordinary reciprocating engine has been adopted under modified circumstances—that is to say, the steam or working fluid is admitted to one end of a work-developing chamber at a time when a piston or moving diaphragm is adjacent to that end. The piston is urged through the chamber against a resistance. On the completion of the stroke the steam is admitted between the piston and the other end of the chamber, so as to drive it through the chamber in the reverse direction, and so on alternately. Now, according to this invention the chamber is a portion of an annular space within a cylinder, and the cylinder is mounted on a shaft, so that it may revolve. The piston-diaphragm moves coaxially with it, the relative movement of piston and chamber being that of a repeated angular oscillation. Further, the engine is so arranged that while the annular chamber revolves at a uniform speed, the piston-diaphragm revolves also, but with varying speed, alternately faster and slower than the chamber. By this means the repeated sweeping of the piston through the chamber from end to end is effected without any reversal of its absolute motion. This movement may be compared with that of the piston of a locomotive-engine, which, when

running, is always moving forward, but with varying velocity—in one stroke faster, in the next slower, than the cylinder and train. The engine may be used as a motive-power engine 55 or as a pump for exhausting or forcing fluids.

In order that my said invention may be most fully understood and readily carried into effect, I will proceed to describe the drawings hereunto annexed.

In the drawings, Figure 1 is a side elevation, partly in section, of an engine constructed according to my invention. Fig. 2 is a transverse section. Fig. 3 is an end elevation with the end frame removed, and Fig. 4 is a 65 plan of the same. Figs. 5, 6, and 7 are separate views of some of the parts. Fig. 8 is an elevation, and Fig. 9 is a plan, of the linkage which I employ when coupling two engines together.

The annular space previously mentioned, or, as in the actual construction, the annular spaces are obtained in the following manner: A cylinder, after it has been truly bored or turned, is divided into two, three, four, or 75 more compartments by radial sectors, which are secured to the cylinder at ends, and also at the cylindrical surface by bolts, so as to provide steam-tight divisions at exactly equal angular distances apart.

The sectors (four in number) are lettered S in Fig. 2, which is a vertical section taken one half through the cylinder, and the other half shows the cylinder end with the cover removed. The sectors extend far enough into 85 the cylinder to touch a comparatively large central boss, B, concentric with the cylinder. Radiating from the central boss and cast with it are four piston-sectors lettered R, two of which are shown in section, and two not so. 90 These piston-sectors extend outward sufficiently, and have a sufficient length, to touch the cylinder, between the cylinder-sectors, along the cylindrical surface, and also along the flat ends, as may be seen in Fig. 2, and 95 also in Fig. 6, which is a development on a flat surface of a cylindrical section taken on the dotted circle *a a*, Fig. 2, the piston-sectors being a little displaced. Thus, when the boss B makes a sufficient angular oscillation—viz., 100 through sixty degrees—relatively to the cylinder, each piston-sector will sweep through

its corresponding compartment from one cylinder-sector to the adjacent one, and fit it throughout the motion. For the purpose of inserting the piston-piece one end of the cylinder is removable, and is the cylinder-cover 5 ⁷⁰ Q, Fig. 1, secured in the ordinary way by bolts at the flange. The cylinder has a central boss, Y, Fig. 1, at the end remote from the cover, which fits into a corresponding recess in the piston-boss B. By means of this boss and by keys the cylinder is secured to the main shaft A, the rotation of which it is the purpose of the engine to obtain. The piston-boss B is secured also by keys to a hollow shaft or sleeve, H, which fits over the main or cylinder shaft A. While the main shaft A extends through the cylinder both ways, the hollow shaft H extends through the cylinder cover end only to a suitable distance to 10 ⁷⁵ enable it to be carried in a bearing. To prevent leakage of steam at this point, a piece, Z, Fig. 1, is provided with spring-rings kept against the piston-boss by the steam pressure and by the compressed packing in the stuffing-box X. At this end the main and hollow shafts terminate in cranks C and P, Figs. 1, 3, and 4, each secured to its shaft by a key. At a suitable radial distance, which may or may not be, but which in Fig. 3 is shown 15 ⁸⁰ to be the same, each crank-arm has a crank-pin, c and p, projecting from the crank-arm, away from the cylinder. The crank-arm P is bent toward C, and its crank-pin p projects to a distance equal to that of c, so that each pin 20 ⁸⁵ terminates in the same plane transverse to the axis of the shafts. The crank-pins c and p are coupled by means of two connecting-links, L₁ and L₂, to two other pins, d₁ and d₂, which project from another crank—a drag-crank, D. 25 ⁹⁰ (Shown in Figs. 3, 1, and 4.) This crank D turns on a pin whose axis is parallel to the previously-mentioned main shaft and set at a suitable transverse distance away from it. 30 ⁹⁵

The crank-pins on the drag-crank D may or 35 ¹⁰⁰ may not be, but in Fig. 3 are shown to be, set at different radial distances, and this for the purpose of causing the movements of the piston-sectors relatively to the cylinder-sectors, which take place during any half-revolution of 40 the cylinder, to be as nearly as possible similar 105 ¹¹⁰ to those which take place during the other half-revolution—that is to say, by the proportions of crank-arms and connecting-links shown in Fig. 3, each half of each single oscillation of the piston is caused to be performed very nearly 45 ¹¹⁵ during each quarter of the revolution of the cylinder. This is important, allowing as it does the time-action of the valve, which will be presently described, to be similar in the 50 two strokes of the piston, and thus enabling 120 ¹²⁵ the engine to be made double-acting and the valve to effect a suitable distribution of steam in both strokes. 55 ¹³⁰

The drag-crank D may, instead of turning 60 on a fixed pin, be secured to a second shaft parallel to the main shaft and turning in suitably-provided bearings. When used as a

pump, the motive power may be provided by this second shaft and transmitted through the drag-crank to revolve the cylinder and piston; or, when used as an engine, it may in some cases be convenient to take off the whole or a portion of the power through this second shaft. The ends of the second shaft or of the pin and that of the main shaft overlap one another only a short distance, if at all, so that the crank-arms C, P, and D may all make complete revolutions. 65 ⁷⁵

Referring to Fig. 3, it will be seen that each link L, together with the two cranks which it connects, form a combination commonly known as the "drag-link coupling," and possesses the property of causing in the revolution the angle between the two cranks to vary, being at one point of the revolution a maximum, and at another a minimum, alternately. By the use of a combination of two drag-link couplings, as shown, this action may be magnified and made to take effect in causing the hollow shaft-crank P, and therefore the piston, to rotate forward and backward relatively to the main shaft-crank C, and therefore the cylinder through an angle the magnitude of which will depend on the proportions between the lengths of the connecting-links L, the crank-arms P ⁹⁰ 95 and C and D, and the distance apart of the centers of the shafts, this angular oscillation of piston in cylinder taking place with a continual rotation of both cylinder and piston always in the same direction. 100

When used as an engine, the high-pressure fluid, when introduced between one side of each of the piston-sectors and the adjacent cylinder-sector, will, in forcing them apart, cause the rotation of both in the same direction—for, though the pressure-force on the piston-sector one way will be exactly equal to that on the cylinder-sector the other way, yet the connecting-link work is such that the leverage of the pressure on one will be in excess of that on the other, and the engine will move in the direction of the superior moment, and the energy of the working-fluid will exert itself with the same effect as if it had operated on a moving piston in a fixed chamber. 110 ¹¹⁵ That there is a difference in the leverage one way or the other may be seen, *a priori*, by an examination of the angles which the links L make with the crank-arms; but it may be better inferred from the principle of virtual velocities, seeing that when the engine moves either the piston or the cylinder travels faster than the other. To this there is an exception—viz., when the piston is at either end of its stroke or oscillation, then, for the instant, the speed of each being the same, the leverage of the steam-pressure is also the same on each, and we have the equivalent of what in the reciprocating engine is called the "dead-center," past which the engine must be helped either by its own stored energy of motion or with the assistance of a second engine coupled to it. One side (which is sufficient) and the outer edge of each piston-sector and the in-

ner edge of the cylinder-sectors are caused to work steam-tight by means of parallel strips of metal being inserted between projecting sides, as shown in Figs. 2 and 6, and kept 5 pressed toward the surfaces of cylinder and piston-boss by centrifugal force and internal springs. The steam is admitted to the cylinder through radial ports in the cylinder end remote from cover. In Fig. 1 the section of 10 the cylinder is taken through the ports.

A circumferential section of the ports taken along the dotted circle *a a*, Figs. 2 and 7, is shown in Fig. 6; and Fig. 7 is a view from the 15 valve end of the cylinder, one-half the valve being removed, the radial ports being shown in black. The port-openings are close to and on each side of each of the cylinder-sectors *S*, which, as shown in Fig. 6, are at the valve side cut away to provide a suitable admission port 20 when the piston is adjacent to the cylinder-sector. On this cylinder end works the valve, covering and uncovering the ports on each side of the cylinder-sector alternately.

The construction of the valve *V* is shown in 25 Figs. 1, 7, and 6. Fig. 7 shows a view of half the valve, as seen from the back of the valve, the other half being cut away to show the cylinder-ports. In this it will be seen that the valve consists of four radial cavities branching 30 at right angles to one another from a central annular space, *E*, surrounding the boss. Sections of these radial cavities are shown in Figs. 1 and 6. Fig. 6 shows that the radial branches are flattened out on each side to give 35 lap to the valve and form the valve-face where it works in contact with the flat cylinder end. By means of the mechanism to be presently described, the valve is caused to rotate with the cylinder, but yet make relatively to the 40 cylinder an angular oscillation similar to that which the piston makes, but through a less angle. In the central position each branch of the valve overlaps equally two of the cylinder-ports, by preference the two which are one on 45 each side of a cylinder-sector. When the valve turns sufficiently to uncover one of each of the pairs of ports, the steam or working-fluid, which, as will be presently described, is supplied to press on the back of the valve, 50 will flow through these ports into the cylinder. At the same time the cavity of each branch will be brought opposite the other of each of the pairs of ports, and allow the fluid which has done its work to flow from the cylinder through the radial cavity to the central 55 annular space, *E*, Figs. 1 and 7, from which it is led by an ejection-passage, *E'*, Fig. 4. The valve works within a stationary steam-chest, *J*, Fig. 1, which incloses and jackets 60 the entire cylinder, and to which the steam is led by the branch *I*. The shafts pass through the stuffing-boxes *X_s* and *X_E*. The steam-chest has a pocket at the bottom, into which water condensed from the steam may drain, 65 and be drawn off when necessary. By the excess pressure of the steam on the cover end of the cylinder the back ring of the valve

forming the outer boundary of the annular exhaust-passage *E* is kept pressed against the casing-cover *F*, Fig. 1, preventing leakage of 70 steam. The amount of this pressure may be regulated by a thrust-collar, *T*, on the main shaft and adjustable bearing, Fig. 1. The motion of the valve is derived from a drag-link mechanism similar to that employed to regulate 75 the movement of the piston in the cylinder. Since the angular travel of the valve is required to be only comparatively small, a small lateral displacement of the center of the drag-crank is sufficient. This is obtained by 80 mounting it on an eccentric disk through a hole, in which the main shaft passes.

Fig. 5 is a view on an enlarged scale of the 85 linkage, as seen from the valve end of the engine.

The drag-crank for the valve consists simply of an eccentric strap in two portions connected by bolts and carrying two pins, *d*₁ and *d*₂, connected by links *L'*₁ and *L'*₂ to the pins *c*' and *v*', which project from the cranks *C'* and *V'*. In 90 Fig. 1 the drag-crank or eccentric-strap is omitted, and the cranks *C'* and *V'* are shown uncoupled; but in Fig. 4 is shown a plan of the mechanism connected up. Like as the piston is secured to a hollow shaft, so the valve 95 is to another hollow shaft or tube, *H'*, which also rides on the main shaft, and to which the crank *V'* is secured by a key. The crank *C'* is secured to the main shaft. The valve-tube passes through the stuffing-box *X_E*. 100

The eccentric disk *W*, on which the valve drag-crank is mounted, may be secured rigidly to the frame-work of the engine, or mounted in such a way that its position may be adjusted at will, as by securing it to a lever, *U*, Figs. 105 5 and 1. By this arrangement the eccentric may be put in a position suitable to give a correct movement to the valve corresponding to a reversal of the motion of the engine; or, further, the eccentric may be placed in position for ahead motion with an earlier performance of its operations on the steam, and thus a variable cut-off derived, similar to that due in the ordinary engine to Stephenson's link motion. 110

The position of the lever may be regulated 115 by a governor, so that when the engine increases in speed the governor may not, as in the ordinary way, act on a separate valve to throttle the steam, but place the lever in such a new position that the valve *V* may cut off the steam earlier.

Two or more engines may be coupled. Thus a high-pressure engine may be coupled with a low-pressure engine, receiving the steam from 125 the high-pressure engine, or engines separately supplied with steam may be coupled. The manner of coupling is shown in Figs. 8 and 9, and may be described as follows: Each engine has a main or cylinder crank. *C_H* represents 130 the crank of the high-pressure engine, and *C_L* the corresponding crank of the low-pressure engine. They are keyed on shafts which represent for the respective engines the shaft *A*.

of the previous figure. Each engine has also a hollow shaft or piston-crank, P_u and P_L , and these, as previously described, are coupled by links to a drag-crank. Now, the main crank 5 of one engine, being provided with two crank-pins, is caused to do the duty of drag-crank to the other engine, and similarly the other to the one, as shown in Figs. 8 and 9. Thus, in the compound engine there are two cranks 10 with three projecting pins of one engine facing two cranks with three projecting pins of the other, the cranks being secured to shafts which are parallel to one another, but not in the same line. By employing links of suitable length 15 to connect the cranks, as shown, an angular interval approximating to a right angle may be obtained between the dead-centers of the two engines. In Fig. 8 is also shown another proportion of lengths of crank-arms suitable 20 to make the two strokes of the piston take place each approximately with each half-revolution of the cylinder.

Engines constructed according to this invention may be worked by water or other fluid-pressure, or may be used as pumps. In engines worked by water-pressure means can be provided by which the distance of the center of the drag-crank from the main shaft may be altered either automatically or at will, so as 25 to alter the angular travel of the piston. Thus, referring to Fig. 1, the crank D may be carried upon a stud upon a block, which is movable in radial guides to and from the center of the shaft A . A screw to traverse the block in the 30 guide by means of a corresponding nut is then provided and a hand-wheel on the stem of the screw. By turning this hand-wheel the engine can be started and stopped and so set as to consume the pressure-water only to the 35 amount necessary to overcome the resistance of the load upon the engine. Thus the engine may be regulated according to the work it has to perform to expend a larger or smaller quantity of the high-pressure water in performing 40 each revolution. Lastly, the engine may, especially when intended for use as a pump, be provided with two separate pairs of piston-sectors, each pair, though of the whole length of the cylinder, radiating from a boss of only 45 half the length, so that half the piston-sector of one will sweep over the boss of the other. Thus, instead of all the piston-sectors moving 50 together, they may move in pairs independently in opposite compartments of the cylinder. The piston-bosses being secured to two 55 hollow shafts, one within the other, to which are also secured cranks, and then the drag-crank being provided with three pins on suitably-branching arms, a linkage of the three 60 pins on the drag-crank with the three pins, one on the cylinder or main shaft crank, and the two piston-crank pins, may be made to cause one pair of pistons to be approximately at the 65 center of the stroke, while the other pair is at the end, and thus obtain a more uniform delivery of the fluid pumped.

Having described in detail and shown by drawings how I propose to construct my engine, I will now point out particularly what I consider to be especially my invention. While 70 other inventors have previously described engines and pumps in which two or more piston-sectors are made by various mechanical devices to chase one another round with varying velocity in a fixed cylinder or chamber, I believe that I am the first to show how the cylinder or chamber may be attached to and caused to rotate with some of the sectors, thus securing the advantages, first, that the sectors may be in pairs in one piece, the fluid-pressures acting in a couple on them, thus avoiding axial pressures, and yet permitting of a suitable admission and rejection of the fluid; and, second, that the piston-friction is for the further reason much diminished, because the cylinder 75 moves to a great extent with the piston.

I claim—

1. The combination of the rotating cylinder or chamber, the sectors with which it rotates, and the piston-sectors rotating alternately faster and slower than the cylinder, substantially 90 as and for the purpose described.

2. The combination of rotating cylinder or chamber having a rotating piston or pistons, caused to oscillate relatively to it by a double 95 drag-link coupling, substantially as described.

3. The combination of rotating cylinder or chamber, rotating piston or pistons, and rotating valve making relatively to the cylinder or chamber an angular oscillation, substantially 100 as described.

4. The combination of rotating cylinder or chamber, rotating piston or pistons, and rotating valve controlled by the double drag-link coupling, substantially as described. 105

5. The combination of the rotating cylinder or chamber, the rotating piston or pistons, the rotating valve, and means for adjusting the center of the drag-crank of the valve-controlling mechanism, substantially as and for the 110 purpose described.

6. The combination of the rotating cylinder or chamber, its sectors, the piston-sectors rotating alternately faster and slower than the cylinder, and means for adjusting the center 115 of the drag-crank of the piston-controlling mechanism, substantially as and for the purpose described.

7. The combination of two coupled engines, having rotating cylinders or chambers and rotating pistons, operating with relation to each other as described, and main cranks, drag-cranks, and links connecting said cranks, whereby the main crank of one engine is made to perform the duty of drag-crank for the other, 120 substantially as and for the purpose described. 125
